UNITED STATES PATENT OFFICE.

TRUE M. AVERY, OF GLENS FALLS, NEW YORK, ASSIGNOR TO UNION BAG & PAPER CORPORATION, OF HUDSON FALLS, NEW YORK, A CORPORATION OF NEW YORK.

BAG MAKING AND PRINTING MACHINE.

Application filed September 30, 1925. Serial No. 59,668.

The present invention relates to improvements in machines for making and printing paper bags and it relates more particularly to machines of the class wherein a paper tube is formed and cut into bag-forming sections and the bag sections are passed successively through a printing mechanism which prints labels or other desired impressions thereon.

10 The primary object of the invention is to provide a novel and improved machine of this class whereby the operations of forming and printing bags are performed rapidly and with certainty, the printed impressions on the bags are accurately and uniformly registered, especially when impressions in different colors are made, the machine is adjustable to enable it to form and print bags of different lengths, it embodies means 15 for stacking the finished bags in piles each of a predetermined or counted number, for delivery, and the various parts of the machine, particularly the printing mechanism thereof, are easily accessible to the attendant.

20 To these and other ends, the invention consists in certain improvements and combinations and arrangements of parts, all as will be hereinafter more fully described, the features of novelty being pointed out particularly in the claims at the end of the specification.

In the accompanying drawings:—

Figure 1 is a side elevation of a combined bag-forming and printing machine constructed in accordance with the present invention;

Figure 2 is an elevation of the machine, as shown in Figure 1, as viewed from the left-hand end thereof, the bag-delivery mechanism being omitted;

Figure 3 represents a horizontal section through Figure 1, taken on the line 3—3 of said figure;

Figure 4 is a detail view, on an enlarged scale, showing the forwarding rolls and their driving and controlling means, as viewed from the left in Figure 1;

Figure 5 is a detail view showing in elevation the main shaft and counter-shaft forming part of the driving means for the breaker arm, the sleeve on the main shaft

through which the breaker arm is driven being shown in section;

Figure 6 is a cross-section taken on the line 6—6, Fig. 5, showing the driving gear 55 for the pinch rolls and the countershaft;

Figure 7 is a diagrammatic view of the lower and upper folder rolls and the cooperative forwarding rolls, and the impression roll and the cooperative printing rolls and 60 a portion of the bag-delivery means;

Figures 8 and 9 are detail views, on an enlarged scale, of the lower folder roll, a portion of the upper folder roll and the cooperative forwarding rolls, the forwarding 65 rolls being shown in operative condition to grip and advance a bag section in Fig. 8, and in relatively separated or non-forwarding condition in Figure 9;

Figure 10 is an end elevation of the lower 70 folder roll equipped with the creaser blade and paste bar;

Figure 11 is a side elevation of the lower folder roll;

Figure 12 is an end elevation, partly in section, of the upper folder roll;

Figure 13 is a side elevation of the upper folder roll;

Figure 14 is a detail view showing the periphery of the upper folder roll and illustrating the bag nipping means; 80

Figure 15 is a detail view of the idler roll which cooperates with the upper folder roll, together with the supporting and controlling means for this idler roll; 85

Figure 16 is an end elevation of the idler roll and its supporting means, as shown in Figure 15, and as viewed toward the right in said figure, the supporting bracket for the shaft being omitted and a portion of 90 the upper folder roll being shown in cooperative relation with the idler roll;

Figure 17 is a detail view of the doffers which assist in transferring the folded or completed bags from the upper folder roll 95 to the impression roll, together with the smoothing plate which cooperates with the impression roller;

Figure 18 is a view of the doffers and smoothing plate mounted on their support- 100 ing shaft;

Figure 19 represents a section on the line

19—19 of Figure 18, looking toward the right;

Figure 20 is an elevation of the impression roll, a portion of the peripheral surface thereof being broken away to illustrate the supporting and operating means for the grippers;

Figure 21 is an elevation of the left-hand end of the impression roll as shown in Figure 20, parts being broken away;

Figure 22 is an elevation of the right-hand end of the impression roll, as shown in Figure 20;

Figure 23 is a detail view of the members of a coupling, one of which serves to connect each gripper to the supporting shaft to effect retraction or opening of the gripper;

Figures 24 and 24^a illustrate, respectively, the left-hand and right-hand ends of the delivery mechanism which stacks the finished bags in piles each of a predetermined or counted number;

Figure 25 is a detail view of the triggers and controlling mechanism whereby the delivery mechanism is caused to operate to stack the finished bags in alternate piles; and

Figure 26 is a detail view of the delivery chute or conveyer which conducts the finished bags from the impression roll to the stacking mechanism;

Figure 27 is a longitudinal sectional view of one of the type or printing rolls;

Figure 28 is a view of the left-hand end of the type roll shown in Figure 27, a portion thereof being broken away;

Figures 29 and 30 are edge views and elevations respectively of one of the pinch bars carried by the type roll;

Figure 30^a is a detail view partly in section, illustrating one of the pinch bar actuating springs and its mounting;

Figure 31 is a side elevation of a portion of the inking mechanism;

Figure 32 is a detail section on an enlarged scale taken longitudinally through the bearing and mounting for one of the ink rolls;

Figure 33 represents a cross-section through the bearing and its mounting, taken on the line 33—33, Figure 32; and

Figure 34 is a detail end view of the bearing removed from the mounting.

Similar parts are designated by the same reference characters in the several figures.

The present invention provides a combined bag-making and printing machine which is adapted to form the bags from bag sections which are cut successively from a tube of paper, the bag sections being operated upon by mechanism which forms a fold at one end thereof to produce a closed bottom, the bag thus formed being printed as it is advanced through the machine, and the printed bags are delivered and stacked in piles ready to be removed from the machine.

65 The preferred embodiment of the invention

is shown in the accompanying drawings and will be hereinafter described in detail, but it is to be understood that the invention is not restricted to the precise construction shown as equivalent constructions are contemplated and such will be included within the claims.

The portion of the machine which forms the paper tube from which the bag lengths or sections are cut may be of the same general type as that illustrated and described in my prior Patent No. 1,539,624, granted May 26, 1925.

This portion of the machine may be here described briefly as comprising a former 1 which is mounted on and extends longitudinally of the main frame or bed 2 and is adapted to receive a flat strip of paper which is fed to the former and folded around it by a folding device 3, in a manner well known to those familiar with bag-making machines of this general class.

The paper tube is fed continuously along the former 1 by a pair of draw rolls 4 which grip the paper tube between them, and the portion of the paper tube which has been advanced beyond the serrated severing edge 5 on the former

is gripped at predetermined periods by bars 6^a on upper and lower pinch rolls 6 which operate at such a speed that the pinched portion of the paper tube will be retarded

90 in its movement relatively to its speed between the draw rolls, thus producing slack in the tube between the pinch rolls and draw rolls while it is held by these rolls. The paper tube is severed at predetermined intervals to form the bag sections by a breaker arm 7 which is fixed to and revolves with a breaker shaft 8 and swings periodically past the severing edge 5 of the former and acts on the slack portion of the paper tube.

A movable knife 9 is pivoted on a shaft 10 and has an arm 11 arranged to be engaged periodically by a cam 12 fixed on the lower pinch roll shaft 13 whereby the knife 9 will be caused to bear against the lower side of the paper tube on the former 1 adjacent to the severing edge 5 of the former immediately

100 prior to the swing of the breaker arm past the end of the former, this knife operating in conjunction with the severing edge 5 of the former serving to sever the bag length from the remainder of the paper tube on lines which produce the mouth and upper

110 or closing flap of the bag. The construction and mode of operation of the draw rolls, pinch rolls, the breaker and the movable knife may be substantially the same as is fully illustrated and described in my prior

115 patent above referred to except that the movable knife is located at the under side of the former, so that it will sever the lower side of the paper tube and the direction of rotation of the breaker arm is reversed, so that

120 in the present instance the breaker arm will swing downwardly past the forward end of

125

130

the former in severing each bag length from the paper tube.

The bag-making mechanism thus far described is, in the present instance, driven from the shaft 13 which is utilized as the lower pinch roll shaft, this shaft being provided with a belt pulley 14 or other suitable means for receiving power from any suitable source. The draw rolls 4 are connected to revolve in unison and in the appropriate directions by gears 15 and 16 which are fixed on the outer ends to their shafts 17 and 18, respectively, and one of the draw roll shafts, the lower shaft 18, receives motion through the gear 16 which is fixed thereon and meshes with an idler gear 19, the idler gear being driven from a gear 20 which is fixed on the shaft 13. In order to enable the draw rolls 4 to be driven at different speeds and thus provide for the severing of bag sections of different lengths for the making of bags of different sizes, the gear 20 is removably applied to the shaft 13, so that other gears of different sizes may be substituted, the variations in the ratio of the gearing thus obtained between the draw rolls 4 and the shaft 13 enabling the paper tube to be advanced at a greater speed when relatively long bags are to be produced and at a relatively slower speed when relatively shorter or smaller bags are to be produced. The intermediate or idler gear 19 between the gears 16 and 20 has the bearing stud 19^a fitted adjustably in a slot 19^b which is concentric with the shaft 18 of the lower draw roll so that the intermediate gear 19 will remain in mesh with the gear 16 while it is adjusted in its slot to mesh properly with the different size change gears 20 that may be placed on the lower pinch roll shaft 13. The breaker shaft 8 is driven by a bevel gear 21 fixed thereon and meshing with a similar gear 22, the latter being fixed on or formed as a part of a sleeve 23 which is loosely or revolvably mounted on the shaft 13, this sleeve also having a gear 24 which is fixed on it and meshes with a gear 25 of the same size located beneath it. The gear 25 is fixed on a counter-shaft 26 mounted in suitable bearings in the bed or main frame 2. The main shaft 13 and the counter-shaft 26 have gears 27 and 28 keyed or otherwise fixed thereon and these gears are connected by an intermediate gear 29 so that the shafts 13 and 26 will be connected to revolve in relatively reverse directions. Through the driving connections just described, or other suitable driving connections, the draw rolls 4 will be driven in directions to advance the paper strip to the forward end of the former and the breaker arm will be revolved in a direction which causes it to swing downwardly past the severing edge on the forward end of the former and the knife 9. The movable knife 9 will be lifted against the lower side

of the paper tube immediately preceding each severing operation by the cam 12 which is fixed on the shaft 13 and cooperates with the finger 11 which is, in turn, fixed to one end of the shaft 10 which carries the movable knife. While a paper tube forming and cut-off device substantially similar to those heretofore used generally has been illustrated and described, it will be understood that any other suitable mechanism may be employed which is capable of producing tubular bag lengths or sections.

The mechanisms which receive the bag sections and perform the operations of folding and thus closing the bottoms thereof and of printing labels or other desired impressions on the finished bags are carried by a supplemental frame 30 which is mounted on the main frame or bed 2 preferably at or toward one end thereof, and in order to enable the machine to be adjusted to the making of bags of different lengths, this supplemental frame is adjustable in a direction longitudinally on the stationary main frame or bed 2 whereby the distance between the bag folding mechanism on the supplemental frame and the forward end of the former 1 may be varied to suit the length of bag to be made. As shown, the supplemental frame 30 is narrowed at its lower portion to form frame members 31 which are adapted to fit between the sides of the stationary frame or bed 2, these frame members being rigidly connected by a suitable number of transverse members 32, and the upper portion of the supplemental frame 30 occupies a position above the upper edges of the side members of the bed 2 forming rests 33 which are adapted to seat on the upper longitudinal edges of the bed. Any suitable means may be provided for shifting the supplemental frame 30 in a direction longitudinally on the bed 2 and for holding the supplemental frame in any desired position of adjustment. As shown, a nut 34 is fixed on a cross member 35 which is attached to the lower portion of the supplemental frame, this nut being arranged to receive a threaded screw 36 which is connected to or formed as a part of a shaft 37. This shaft is journaled in a bracket 38 which is fixed to the relatively stationary bed 2 and has a bevel gear 39 fixed thereon and meshed with a bevel gear 40, the latter being fixed to a cross-shaft 41 which is journaled in suitable bearings 43 in the bracket 34 and is extended to one side of the bed and provided with a hand-wheel 44 by means of which it may be rotated. The screw and nut connection thus provided between the bed and the longitudinally movable supplemental frame enables the latter to be easily and quickly shifted longitudinally of the bed to adjust it for the making of bags of different lengths, and when the supplemental frame

has reached any desired position of adjustment, it will be held in such position by the screw and nut connection. It will be understood, however, that other suitable means 5 may be provided for adjusting the supplemental frame longitudinally of the bed and for holding it in different adjusted positions.

Each bag section delivered from the bag former is received by upper and lower folder rolls 45 and 46 which are mounted on shafts 47 and 48 which are journaled in suitable bearings in the sides of the supplemental frame 30, the nip of these rollers being located preferably in substantial alinement 15 with the bag former. The lower folder roll is so driven that it makes one revolution for each bag section received by it, the shaft 48 of this roll having a gear 49 idly mounted thereon and arranged to mesh with an intermediate gear 50, which, in turn, meshes with a gear 51 which is fixed on the shaft 13. The longitudinal adjustment of the supplemental frame 30 will vary the distance between the lower folder roll shaft 48 which is carried 25 by the supplemental frame and the shaft 13 which is mounted in bearings on the stationary main frame or bed, but the driving connection between these shafts may be maintained by the intermediate gear 50, the bearing studs 50^a of which is adjustable in a slot 50^b concentric with the center of the shaft 13 whereby the gear 50 may be adjusted to maintain it in mesh with the gear 49 while said gear 50 remains in mesh with the gear 51. Suitable gearing is provided to connect the lower folder roll shaft with the shaft 47 of the upper folder roll. Preferably, the upper folder roll is of a diameter double that of the lower folder roll and it 35 is connected to revolve at one-half the speed of the lower folder roll, the upper folder roll shaft 47 being shown provided in the present instance with a gear 52 which is fixed thereon and meshed with the gear 49 idle on the lower folder roll shaft 48, the gear 52 being double the diameter of the gear 49. The opposite ends of the upper and lower folder roll shafts 47 and 48 are connected by a pair of gears 53 and 54 which are fixed on these 45 shafts, the gear 53 being double the diameter of the gear 54. The gears 53 and 54 thus maintain the proper relationship between the upper and lower folder rolls, and by reason of the idle mounting of the gear 49 on the lower folder roll shaft, longitudinal adjustment of the frame 30 carrying the folding and printing mechanisms may be accomplished without disturbing the relationship between the upper and lower folder rolls.

The lower folder roll 46, as shown in Figures 7, 10 and 11, is provided with a creaser blade 55 and with an adjacently located paste bar 56, the paste bar being of a length 55 which conforms with the width of the bags

to be made, and it is fitted at its ends in slots 57, formed in clamps 59, the latter being mounted on the shaft 48 at opposite ends of the lower folder roll and clamped in fixed position thereon by tightening of clamping screws 60 with which they are provided. The ends of the paste bar may be secured in the clamps 59 by screws 61. The body portions of the blade 55 and bar 56 lie in a slot or recess 62 which extends longitudinally across the face of the lower folder roll, the blade 55 being secured against one wall thereof as by the screws 58, and this slot or recess is preferably of sufficient circumferential width to permit adjustment of the distance between the bar 56 and the blade 55 to compensate for end folds of different lengths by rotation of the clamps 59 on the roll shaft. The edges of the blade 55 and bar 56 project beyond the circumference of the lower folder roll, the paste bar 56 projecting for a distance greater than that of the creaser blade 55.

The upper folder roll 45 is provided with means to cooperate with the creaser blade 55 whereby a crease will be formed across the forward end of each advancing bag section and such bag section will be nipped at the crease to form the bottom fold of the bag and to hold the bag section to the upper folder roll during its travel therewith. Preferably, and as shown, the upper folder roll is provided at diametrically opposite points in its circumference with bars 63 which are inserted flush with the circumferential surface of the roll and each bar forms a nipping edge 64. A shaft 65 is rotatably mounted in each bar 63 and carries a nipper blade 66 which is movable toward and from the nipping edge 64 incident to rotation of the respective shaft 65. Each of the shafts 65 is provided with a spring 67 which acts to yieldingly rotate the shaft in a direction to move the nipper blade 66 toward the relatively stationary nipping edge 64 and to hold the doubled edge of a bag section nipped between them, and means is provided for rotating each shaft 65 to retract the nipper blade 66 when the nipping means reaches its cooperative relationship with the creaser blade 55 of the lower folder roll incident to the rotation of the upper and lower folder rolls. The latter means consists preferably of a crank arm 68 which is fixed to the end of the respective shaft 65 and carries a roll 69 which is arranged to engage and travel on a cam 70, the latter being mounted on or formed as a part of a bracket 71 which may be bolted or otherwise secured to the adjacent side of the frame 30. The track 72 of this cam on which the rollers 69 are adapted to travel is substantially concentric with the axis about which the upper folder roll 45 revolves and its length determines the 130

periods during which the nipper blades 66 are in nipping and released positions. The upper and lower folder rollers are so connected by their gearing that when the creaser blade 55 of the lower folder roll approaches a position in alinement with the centers of the upper and lower folder rolls, the nipping edge 64 will lie at one side of the creaser blade 55 while the nipper blade 66 will lie at the opposite side of the creaser blade, the nipper blade at this time being held in its open or retracted position by the roller 69 which is connected thereto and still rests upon the cam 70. By spacing apart the creaser blade 55 and the paste bar 56, as shown in Fig. 7, a space is provided between these parts in which the nipper blade 66 may be accommodated. As the nipping means on the upper folder roll and 20 the creaser blade on the lower folder roll approach this position the leading end of a bag section, indicated at *a*, which has been advanced to the folding mechanism, will lie between the folder rolls, and as the latter 25 revolve in the direction of the arrows in Figure 7, the portion of the bag section adjacent to but in rear of its leading edge, will be pushed by the exposed edge of the creaser blade 55 into the gap provided between the 30 nipper edge 64 and the retracted nipper blade 66. A portion of the periphery of the lower folder roll 46 in advance of the creaser blade 55 is preferably recessed or cut away, as at 73, to avoid gripping of the 35 portion of the bag section in advance of the creaser blade 55 between the closely adjacent surfaces of the upper and lower folder rolls, so that the portion of the bag section adjacent to the creaser blade is free to be forced into the gap or recess formed between the nipper blade 66 and the nipping edge 64. Immediately after the folder rolls have revolved sufficiently to carry the creaser blade 55 beyond a position in alinement with 40 the centers of the folder rolls, the roller 69 connected to the nipper blade 66 passes off the end of the cam 70 and the spring 67 connected to the shaft 65 which carries the nipper blade acts immediately to close 45 the nipper blade 66 against the nipping edge 64 as the edge of the creaser blade 55, which is preferably pointed, or relatively sharp, is withdrawing from a position between the nipper blade 66 and the nipping 50 edge 64, in consequence of which the portion of the bag section which was forced into this space by the creaser blade will be nipped along its creased edge and will be firmly held between the nipper blade 66 and the nipping edge of the upper folder roll. In order to facilitate accurate timing of the 55 movements of the nipper blade 66 to and from nipping position, the cam 70 which controls the movements of the nipper blade 60 may comprise relatively adjustable cam sec- tions 70^a which, as shown in Figures 12 and 13, are adjustable in a direction circumferentially of the cam and thus enable the ends of the cam onto and from which the rollers 69 pass to be accurately located. 70

Means is provided for applying a line of paste or adhesive to the portion of the bag section adjacent to the creased and nipped portion thereof. As shown in the present instance, the paste is applied to the bag section in rear of the portion thereof which is creased and nipped, by the paste bar 56 which is located on the lower folder roll in rear of the creaser blade 55. During rotation of the lower folder roll the edge of the 75 paste bar which projects outwardly beyond the creaser blade comes into contact with a paste covered roll 74 which is mounted to revolve in the upper portion of a paste box 75 so that its periphery will be touched by the edge of the paste bar 56 as the latter revolves past it, the paste thus transferred to the outer edge of the paste bar being applied to the bag section adjacent to but in rear of the creased and nipped portion 80 thereof. The periphery of the upper folder roll 45 is provided with a recess 76 in rear of each nipper blade 66 therein into which the portion of the bag section engaged by the paste bar may be pressed more or less, the inherent resilience of the paper composing the bag section insuring sufficient yielding pressure between the bag section and the paste bar to effect the application of a sufficient amount of paste thereto. The paste 85 roll 74 may be kept supplied with paste by providing a cooperating paste roll 77 which is submerged or immersed to a sufficient depth in a body of paste contained in the paste box 75, the paste rolls 74 and 77 being arranged to maintain contact with one another and being rotated during the operation of the machine, so that they have a substantially rolling engagement by gears 78 and 79 which are fixed to the shafts 80 and 90 of these rollers. A driving gear 82 fixed on a shaft 83 meshes with the gear 79 and serves to drive the paste rolls 74 and 77 continuously, the shaft 83 being connected by bevel gears 84 and 85 to a shaft 86 and the latter being connected, in turn, by a worm wheel 87 and a cooperating worm 88 to the lower folder roller shaft 48 to which the worm is fixed. 95

Means is preferably provided for forwarding the severed bag sections from the former to the upper and lower folder rolls. As shown in the present instance, such forwarding means comprises a pair of forwarding rolls 89 and 90 which are mounted at the side of the folder rolls which is toward the delivery end of the former, the lower forwarding roll, as will be seen from Figures 4, 8 and 9, being mounted at its ends in relatively fixed bearings 91 formed in brackets 100 105 110 115 120 125 130

92 which are bolted or otherwise fixed to a transverse member 93 which is attached to or forms part of the lower portion 31 of the adjustable supplemental frame. The 5 upper forwarding roll 89 has its shaft mounted in bearings 94, which are slideable in guides 95 formed in the upper portions of the brackets 92, so that the upper forwarding roll may move into and out of operative relation with the lower forwarding roll. A compression spring 96 bears on each 10 of the bearings 94 and acts to yieldingly hold the upper forwarding roll in bag-advancing relation with the lower forwarding roll. The forwarding rolls are connected to revolve in unison and in directions to advance a bag section to the folder rolls by gears 97 and 98 which are fixed on the shafts 15 of these rolls, and the forwarding rolls are driven continuously by a gear 99 which meshes with the gear 98 on the lower forwarding roll and with the gear 54 which is fixed on the shaft 48 of the lower folder roll 46.

20 While the forwarding rolls are thus driven continuously during the operation of the machine and at a speed that will advance the bag sections to the folder rolls to conform substantially with the speed with 25 which the bag sections are passed between these folder rolls, means is preferably employed for interrupting the advance of each bag section by the forwarding rolls after such bag section has been nipped by the folder rolls. For this purpose, a cam 100 is provided on the shaft 48 of the lower folder roll, the raised portion 101 of this cam being arranged to operate upon a roller 30 which is carried by an arm 103, the latter being fixed to a shaft 104 which is mounted to rock in the brackets 92. The driving gear 99 for the forwarding rolls may be loosely mounted on this shaft 104 as a supporting journal. The shaft 104 has a pair 35 of arms 105 fixed thereon and these arms are arranged to bear against pins 106 which are guided to move longitudinally in the respective brackets 92 and to bear at their upper ends against the bearings 94 for the opposite ends of the upper forwarding roll. While the roller 102 is riding on the low 40 part of the cam 100 with which it is held in contact by the springs 96 which act through the pins 106, rock shaft 104, arms 105, and arm 103, the upper forwarding roller will be pressed toward the lower forwarding roll and the forwarding rolls will then be in condition to advance a bag section to the folder rolls. However, after the 45 uppermost end of a bag section has been introduced to the proper extent between the upper and lower folder rolls, which occurs when the creaser blade and paste bar on the lower folder roll and the nipping means on the upper folder roll approach the po-

sition shown in Figure 7, the high part 101 of the cam will have reached the roller 102, and as the operation of the machine continues, the roller 102 will be forced outwardly or away from the lower folder roll 70 shaft 48, and in so doing, the pins 106 are actuated to lift the bearings 94 and thereby separate the upper forwarding roll from the lower forwarding roll to an extent sufficient to cause these forwarding rolls to release 75 their grip upon the interposed bag section. As the foremost end of the bag section at this time is gripped between the folder rolls, the latter are enabled to act properly upon the bag section to crease and nip it and to effect the further advance of the bag section without interference from the forwarding rolls.

The cam 101, which controls the advance and release of the bag section by the forwarding rolls is preferably split or formed of two disk-like sections which are relatively adjustable in a circumferential direction in order to vary the length and the positions of the ends of the raised portion 101 thereof on which the roller 102 rides, thus enabling the forwarding rolls to be properly timed in their operation to grip the bag section and feed its foremost end into position between the folder rolls and to interrupt this feeding of the bag section after the leading edge of the bag section has been advanced beyond the creaser blade 55 to produce a bottom fold of the desired depth. After the cam has been properly set, the forwarding rolls will operate to insure uniform depth of the bottom folds on all bags made according to such adjustment.

The nipping of the leading end of the bag section by the nipper blade 66 of the upper folder roll causes the forward edge a' of the bag section to project outwardly from this folder roll, and as this folder roll rotates in the direction indicated by the arrow in Figure 7, the nipped bag section will be advanced while lying against the periphery of this roll until it reaches an impression roll 107 which is mounted above the upper folder roll 45 in suitable bearings provided in the sides of the adjustable frame 30. Means is provided for folding this outwardly projecting edge of the bag section down against the portion of the bag section in rear of the crease therein and to which paste was previously supplied by the paste bar 56. As shown, such means comprises an idler roller 108 composed preferably of rubber or other relatively yielding material, the ends of the shaft 109 of this roller being revolvably mounted in bearings 110 formed in the upper ends of a pair of arms 111. Means is provided for yieldingly holding the roller 108 in contact with the peripheral surface of the folder roll 45 or with a bag section thereon, and preferably, the oppo-

site ends of this roller 108 are capable of relatively independent movement toward or from the folder roll 45, whereby the idler roll may equalize its pressure on the bag section and accommodate itself to irregularities of the surface engaged by it. As shown in the present instance, the arms 111 are loosely mounted on a shaft 112, each end of which may be fixed to a bracket 113 which is bolted 19 or otherwise secured to a side of the frame 30, the arms 111 being capable of independent rotation on the shaft, and a spring 114 is provided for each of these arms, one end of the spring engaging the respective arm, 25 and the other end of the spring engaging a collar 115 which is fixed on the shaft 112. The springs 114 act to yieldingly compress and hold the roller 108 against the surface of the folder roll 45 or a bag section thereon 30 and as the outstanding edge *a'* at the leading edge of the bag section encounters the roller 108, it will be folded back and against the pasted portion of the bag section, thus effecting the pasting of the bottom fold of 35 the bag. In order to prevent dropping of the roller 108 into the longitudinal recess which is formed in the periphery of the folder roll 45 adjacent to the nipper blade 66 and thus avoid damage to the roll 108 40 or interference with the proper performance of the folding and pasting operation by this roller, means is provided for limiting the extent of inward movement of the roller 108 without, however, interfering with its 45 movements while operating upon the bag section. For this purpose, the roller 108 is made of such length that its ends will ride on the circular end plates 45^a of the upper folder roll which have a diameter equal to 50 that of the latter roll. A stop arm 116 may be provided for each of the roller-carrying arms 111, these stop arms being clamped or otherwise adjustably fixed on the shaft 112 alongside of the respective roller carrying arm, and each stop arm has a pin 117 fixed 55 therein and arranged to operate in a segmental slot 118 in the respective roller-carrying arm 111, the slot 118 being concentric with the shaft 112. The stop arms 116 are 60 so set on the shaft 112 that when the idler roll 108 is in proper working relation with the surface of the folder roll 45, the pin 117 on each stop arm will be in engagement with or in close proximity to the outer end of the 65 segmental slot 118, and, hence, when the roller 108 is removed from the arms 111, the latter will be held from swinging inwardly and thus allowing unwinding of the springs by the abutting of the outer ends of the slots 70 118 on the arms 111 against the stop pins 117. These seats 118 and pins 117 however will not interfere with the yielding movements of the roller 108 in a direction away from the upper folder roll and they will permit 75 the arms 111 to be drawn back from the

upper folder roll to a sufficient extent to facilitate removal or replacement of the roller 108.

The impression roll 107, which is mounted on a shaft 119, the ends of which are journaled in bearings in the sides of the supplemental frame 30, is preferably of the same diameter as the upper folder roll 45 and it is driven at the same peripheral speed therewith and in a direction to advance the bag sections between it and the upper folder roll. In the present instance, the shafts 47 and 119 of the upper folder roll and the impression roll are connected by gears 120 and 121 which are of equal size and form a direct connection between them. The impression roll which is shown particularly in Figures 7 and 20-23, inclusive, is faced with suitable packings or "make ready" 122 which insure effective impressions upon the bag sections 80 lying against them by the type on the printing rolls 123 and 124 which latter, together with the inking mechanism above them, are driven by a train of gearing 121^a driven from the gear 121. In the present instance, 85 where one bag section on the impression roll will be in process of printing while another bag section will be in course of transfer to the impression roll from the upper folder roll, a pair of these packings are provided at 90 diametrically opposite sides of the impression roller. Each packing, which may be composed of a strip or sheet of flexible yielding material, such as that commonly used in the printing art, is secured at one end to the impression roll by doubling such end about an edge 125 formed in the circumference of the impression roll and arranging its terminal edge to be engaged by impaling pins 126 which are fixed in the periphery of the impression roll and have pointed ends projecting inwardly therefrom. This end of the packing is retained in engagement with the impaling pins by a clamping plate 127 which is fixed to and extends longitudinally of a 95 shaft 128, the latter being mounted rotatably in heads 129 forming the ends of the impression roll, and this shaft is provided with means for rotating it whereby the clamping plate 127 may be brought into gripping relation with the impaled edge of the packing or it may be swung clear of such edge of the packing to permit insertion or removal thereof incident to renewal. As 100 shown, an end of each shaft 128 is provided with a crank 129^a which is fixed thereto and carries a nut 130 and a screw 131 is engaged in the nut and extends through a lug 132 secured to the adjacent head of the roll, the screw having thrust collars 133 which prevent axial movement of the screw although permitting rotation thereof in the lug. An angular end 134 is formed on the screw to receive a wrench 105 whereby the screw may be rotated. Rota- 110

tion of the screw in one direction will swing the clamping plates 127 against the impaled edge of the packing and will firmly secure this edge of the packing in place, whereas 5 rotation of the screw in the opposite direction will swing the clamping plates 127 in a direction to release the impaled edge of the packing and permit a new packing to be put in place. The opposite end of each packing 10 is attached to a shaft 135 which is rotatably mounted in the heads 129 forming the ends of the impression roll, and one end of this shaft has a squared or other angular portion 136 thereon to receive a suitable wrench 15 whereby this shaft may be rotated and thus caused to wind this end of the packing thereon. Winding of the packing on the shaft 135 serves to properly tension the packing on the surface of the impression roll, and the 20 packing may be held under proper tension by a locking pawl 136 which may be pivoted on the adjacent roll head and arranged to cooperate with a ratchet disk 137 fixed on the shaft 135.

25 The impression roll carries grippers which serve to receive the bag sections from the upper folder roll and to retain them on the impression roll while the bag sections are being carried past the printing roll or rolls, 30 these grippers, in the present instance being provided at diametrically opposite sides of the impression roll. A pair of these grippers 138 is preferably provided at each side of the impression roll. The grippers of 35 each pair are loosely or rotatably mounted on a shaft 139, the ends of which are rotatably mounted in bearings 140 formed on the heads 129, and the grippers are in the form of relatively flat fingers, the free ends of 40 which are bent so that they will overlie and bear flatwise against an adjacent end of the respective packing. Means is provided for yieldingly pressing the grippers toward the packing whereby they will produce and 45 maintain a firm grip upon the leading edge of a bag section interposed between them and the packing, and preferably the grippers are capable of acting independently to a sufficient extent that will enable them to 50 compensate for irregularities in the packing surface or variations in the edges of the bag sections engaged by them. As shown, a separate spring 141 is provided for each gripper, one end of the spring being connected to the gripper and the opposite end thereof connected to a collar 142 which is 55 fixed on the shaft 139. The shaft 139 has a crank arm 143 fixed thereon beyond an end of the roll, and this crank arm carries 60 a roller 144 which is arranged to travel on a cam 145, this cam being formed on or attached to a bracket 146 which is bolted or otherwise secured to the adjacent side of the frame 30. The cam acting on the 65 roller 144 of each of the shafts 139 serves

to retract the grippers at appropriate periods in the rotation of the impression roll to release a printed bag for delivery and to receive another bag preparatory to printing. While the grippers 138 are capable of 70 acting independently under the influence of their springs 141 to insure equal and effective gripping action on the bag sections, means is provided for causing retraction or opening movement of the grippers when the 75 shaft 139 is rocked by the riding of the roller 144 thereon on the cam 145. Such means, in the present instance, comprises a coupling formed by a sleeve extension 147 on the gripper support and a similar sleeve extension 80 148 on the respective collar 142, the sleeve extension 147 having notches 149 therein to loosely receive lugs 150 on the sleeve extension 148, whereby relative rotation may occur between the gripper and its 85 respective collar 142 to a limited degree, but when the shaft 139 is rocked under the action of the cam 145 to retract the grippers, a driving connection will be effected between 90 each of the collars 142 and its respective gripper whereby the grippers will both be retracted. The shaft 139 is provided with a spring 151 which acts yieldingly thereon to rotate it in a direction to cause engagement of the grippers with the packing on 95 the impression roll and to hold the roller 144 in engagement with the cam 145.

100 The cam 145 is so shaped and located that when the impression roll reaches a position in its rotation where a pair of grippers thereon are approaching or are opposite to the printing rolls, the grippers will be in gripping position, but after the grippers have passed the printing roll or rolls the grippers will be swung outwardly from the 105 impression roll, thereby releasing the bag section previously held by them, so that such bag section may be delivered, and, as the impression roll continues its rotation, the cam will hold the grippers in open position until another bag has been transferred from the upper folder roll to the impression roll. As the grippers are in open position while they are passing over the top of the 110 upper folder roll 45, the folder roll is provided with recesses 152 which are located in its circumference at points adjacent to the nipper blade 66 therein, the open grippers being accommodated in these recesses 115 while they are passing over the top of the 120 upper folder roll.

125 The bags are released from the upper folder roll 45 and transferred to the impression roll at the moment the leading or nipped edge of each bag reaches a position substantially in alignment with the centers of these rolls. The release of the nipped edge of the bag is effected by the riding of the roller 69 connected to the nipper blade 130 onto the cam 70, and at this moment the

grippers carried by the impression roll are in open position and lying in the recesses 152 immediately adjacent to the nipper blade 66. The inherent resilience of the paper 5 composing the bag will act to flatten the sharply folded nipped edge of the bag immediately upon its release by the nipper and such flattening of the edge of the bag causes the leading edge of the bag to move toward 10 a position between the grippers and the surface of the impression roll. In order to insure prompt and effective transfer of the bag from the folder roll to the impression roll, a suitable number of doffers 153 are 15 provided, these doffers being pointed so that they extend inwardly between the upper folder roll and the impression roll to substantially the point of nip between these rolls and the doffers preferably project into 20 grooves 154 which extend continuously in a direction circumferentially of the upper folder roll, the outer edge of the nipper blade 66 being also provided with notches 155 which are alined with the grooves 154 and permit the nipper blade to pass the doffers. The doffers which lie close to the surface of the impression roll provide guides onto which the bags are advanced as the folder roll continues its rotation, the doffers 25 thus acting to strip or remove the bag section from the folder roll and to direct it around the impression roll. As the rotation of the upper folder roll and the impression roll continues, the roller 144 passes off the 30 high part of the cam 145 whereupon the spring 151 acts to swing the grippers into closed or gripping position. As the shaft 139 which forms the center about which the grippers swing is located inwardly from 35 the periphery of the impression roll, the ends of the grippers, while swinging into closed or gripping position will move to some extent in a direction circumferentially of the impression roll, thereby bringing the 40 free ends of the grippers into positions to lap over and engage the leading end of the bag section, and the grippers will clamp and hold the leading edge of the bag section in engagement with the packing on the impression roll until the grippers are opened by the cam 145 to release the bag section for 45 delivery.

The doffers 153 may be clamped or otherwise secured in position on a supporting shaft 50 156, the ends of which may be fixed in the sides of the frame 30, and this shaft may also serve as a support for a smoothing plate 157 that may bear on each bag on the impression roll as it is carried toward the printing roll 55 to remove any wrinkles therein. This smoothing plate, as shown, is mounted on arms 158 which are loosely supported on the shaft 156 and separate springs 159 are provided between the arms 158 and collars 160 fixed on the shaft whereby the ends of the

plate may yield more or less independently in order to equalize the pressure exerted by the plate on the bags and to enable the plate to accommodate itself to obstructions or irregularities in the bags as they are carried 70 around the impression roll. The limits of swinging movement of the smoothing plate may be determined by pins 161 which project from the outer sides of the arms 158 and operate in notches 162 formed in the inner 75 sides of collars 163 which are clamped or otherwise fixed in appropriately adjusted positions on the shaft 156. The operative edge of the smoothing plate is formed with notches 164 which enable the grippers 138 80 to pass without striking it. This smoothing plate, as will be seen from Figure 7, insures smoothing and proper tensioning of the bag while passing the printing rolls 123 and 124. 85

In order to more sharply crease the bottom fold of the bag and thereby avoid tendency to spring open, each type roll 123 or 124 is provided with a pinch bar 123^a or 124^a positioned and operative to bear directly on the bottom fold of the bag and press it against the packing on the impression roll as the bottom fold passes the respective type roll and substantially at the time the type apply ink to the bag. The pinch bars 90 and their operating means on one of the type rolls are shown in Figures 27 to 38 wherein a pair of these bars are employed, they being located respectively at diametrically opposite sides of the type roll and are guided 100 by the slots 240 to reciprocate radially of the roll. Each pinch bar is provided with racks 241 with which mesh pinions 242 fixed on a shaft 243, a spring 244 normally acting on the shaft to rotate it and the pinions 105 in a direction to draw the pinch bar inwardly. The shaft 243 also has an arm 245 fixed thereon, this arm carrying a roller 246 which rides on a stationary cam 247 which may be bolted or otherwise fixed to the adjacent side of the main frame. The roller 246 is held in contact with the cam by the spring 244, and the cam is so shaped that as the rotation of the type roll brings the pinch bar into a position to register with the bottom fold of the bag which is being advanced by the impression roll, the pinch 110 bar will be forced outwardly relatively to the type roll thus causing it to press the bottom fold of the bag firmly against the packing on the impression roll, thereby more sharply creasing the fold and thus removing any tendency thereof to spring open. As the further rotation of the type roll carries the pinch roll away from the impression roll, the shape of the cam 247 allows the spring 244 to draw the pinch bar inwardly relatively to the type roll. The outer edge of each pinch bar is notched as at 248 115 to accommodate and thus clear the grippers 120 to 125 130

138 on the impression roll which hold the folded bottom of the bag while the pinch bar presses thereon. The printing type may be locked on the type roll by pairs of clamps 5 249, which may be adjusted and held by suitable screws 250.

When the leading edge of each bag has passed the second printing roll 124, the roller 144 rides upon the raised portion of the cam 10 145, thereby swinging the grippers holding this bag into open position. The leading edge of the bag, when thus released, has a tendency to swing outwardly or away from the surface of the impression roll, due to 15 the resilience of the paper composing the bag, and the printed bag is then ready to be delivered to doffers 165 which extend into close proximity to the surface of the impression roller. To complete the delivery 20 of the printed bag from the impression roll and to insure its proper entrance into a chute provided for its reception, a pair of rubber or other relatively yielding rollers 166 are preferably provided which are arranged to bear on the bag at points somewhat beyond the ends of the doffers 165. These rollers are provided with means for 25 yieldingly pressing them against the impression roller and preferably they are capable of acting independently of one another. As shown particularly in Figure 26, these rollers 166 are supported on the outer ends of arms 167, said arms being loosely or rotatably mounted on a shaft 168 and separate 30 springs 169 which are interposed between the arms 167 and collars 170 which are clamped or otherwise adjustably fixed on the shaft 168 act to independently force the rollers 166 into contact with the extreme 35 longitudinal edges of a bag on the impression roll and at the outer sides of the grippers.

Means is provided for retracting the rollers 166 as the leading edge of a bag about to be delivered approaches it and for causing 40 these rollers and the doffers to move into operative position to effect delivery of the bag. As shown, arms 167^a are fixed to the shaft 168 beside each roller-carrying arm 167 and are recessed to receive pins 167^b fixed to the respective arms 167. An arm 168^a is fixed to the shaft 168 and carries a roller arranged to ride on a cam 119^a fixed on the shaft 119 under the action of a spring 119^b. The cam 119^a is so shaped that it 45 will allow the spring 119^b to hold the rollers 166 against the surface of the impression roll or a bag thereon, but as the leading end of a bag or the impression roll approaches these rollers, the cam 119^a will act to rock the shaft 168 in a direction to cause the arms 167^a to engage the pins 167^b and thereby 50 retract the rollers 166, and after the leading end of the bag has passed these rollers, the shape of the cam 119^a allows the spring 60 119^b to swing these rollers into engagement

with the bag on the impression roll as it is being delivered from the printing roll 124, said rollers thus acting to strip the bag from the type on the printing roll while it is being delivered therefrom. The doffers 165 are 55 preferably fixed to the shaft 168 so that they will swing to and from operative position in substantial unison with the corresponding movements of the rolls 166. By thus retracting the rollers 166 and the doffers 165 while the grippers on the impression rolls are passing, striking of these rollers against the leading or bottom edge of the bag and consequent folding back of the corners of the bag is avoided. The shaft 168 may be 60 supported by brackets 30^a fixed on the sides of the supplemental frames 30.

The doffers 165 and rollers 166 are preferably located at the entrance to a delivery chute through which the printed and completed bags are discharged. The delivery chute employed in the present instance, and as shown in Figures 1, 7 and 26, comprises a pair of endless belts 171 which pass over idler rollers 172 which may be loosely journaled on the shaft 168 at one end of the chute and over driving pulleys 173 on a shaft 174 which is mounted in bearings 175 at the opposite or lower end of the chute, these travelling belts providing a surface on which the printed bags may rest and with which they may travel during their discharge from the machine. The shaft 174 to which the belt-driven pulleys 173 are fixed may be driven by gears 176 fixed thereon and arranged to mesh with gears 177 which, in turn, are fixed on a shaft 178 which is mounted in bearing brackets 179 located at the delivery end of the machine, the shaft 178 being provided with a belt pulley 180 to receive a driving belt 181 which passes over a belt pulley 182 fixed on the lower folder roll shaft 48. The chute may have side members 183 to connect the shafts 168 and 174 and to support the various parts of the chute, guides 185 being preferably provided at the sides of the chute to prevent lateral displacement of the bags. The intermediate portions of the upper stretches of the travelling belts may be supported by idler rollers 186 which may be mounted on a cross-member 187 which connects the side members 183 and intermediate tensioning rollers 188 may also be provided to engage the lower stretches of the belts, these tensioning rollers being shown mounted on arms 189 which are pivoted to swing about the cross-member 187.

The guides 185 are preferably adjustable laterally in order to accommodate the chute to bags of different widths. For this purpose, a plate 190 having slotted lugs 191 formed thereon is clamped by the screws 192 to the opposite sides of the frame members 183 toward the upper end of the chute, this 130

plate having transversely extending slots 193 therein and a similar plate 194 is provided toward the lower end of the chute, this plate having slotted lugs 195 which are adjustably clamped by the screws 196 to the outer sides of the respective frame members 183, this lower plate also having transversely extending slots 197 therein. The guide members 185 extend beneath the slotted portions of the plates 190 and 194 and they carry clamping screws 198 and 199 which are adjustable longitudinally in the respective transverse slots 193 and 197 of the plates 190 and 194 when the screws are loosened, thereby permitting transverse adjustment of the respective guide, and when these screws are tightened, the guides are secured in adjusted position. These guides 185 serve not only to prevent displacement 20 of the bags laterally from the conveyer belts but they are flanged, as shown, so that they overhang the lateral edges of the bags on the conveyer belts, and thus prevent displacement of the bags by movement thereof 25 in a direction away from the bag-supporting surface of the conveyer belts.

The finished and printed bags are delivered from the lower end of the delivery chute to a suitable receptacle in which they 30 are piled or stacked in condition for removal in convenient form from the machine. The present invention provides delivery means which is capable of stacking a predetermined number of bags in a pile, whereupon the stacking of the bags in that pile is interrupted and the bags are stacked to form another pile to contain a predetermined number of bags, the operations of forming the successive piles being controlled 35 automatically.

The bag-stacking means is shown particularly in Figures 24, 24^a and 25. In the present instance, a duplex bag receiver providing a pair of bag-receiving compartments 200 and 200^a is employed, this bag receiver being mounted on a carriage which is shiftable in a direction transversely of the delivery chute whereby either one or the other of the bag-receiving compartments may be brought into position to receive and stack the bags delivered by the chute. The bag receiver may be constructed in different ways. As shown, it comprises a rear wall or plate 201 which forms the back of both bag-receiving compartments, and a bottom plate 202 which forms a stop and support for the bottom edges of the bags as they are delivered into the receiver. The different bag compartments of the receiver are separated by vertical partition plates 203 which may be located midway of the receiver and the outer side walls of the compartments are formed by plates 204 which are arranged vertically at the front of the rear plate 201 toward the opposite ends

thereof. These end plates 204 are preferably adjustable in a direction toward and from the intermediate partition plates 203 in order to set the width of the compartments to conform with the width of the bags being made. For these purposes, each of the end plates 204 may be provided with a laterally extending flange 205 which is adapted to partly overlap and lie flatwise against the face of the rear plate 201, and this flange is provided with a suitable number of longitudinal slots 206 to receive screws 207 which, when tightened, will serve to hold the end plates in adjusted position. It will be observed from Figure 1 that the upper edge of the rear plate 201 of the bag receiver is positioned below and in approximate alignment with the chute, so that it will receive the bags delivered thereby.

The carriage which supports the bag-receiver for movement in a direction transversely of the discharge end of the delivery chute whereby one or the other of the bag-receiving compartments may be brought into position to receive and stack the bags comprises, in the present instance, a frame 208 which projects to or beyond the ends of the bag receiver and is formed with bearings 209 which are adapted to slide freely on guide rods 210. These guide rods are fixed at their ends in frame members 211, these frame members being parts of a frame 212 which is bolted or otherwise secured to the adjacent end of the lower portion 31 of the adjustable supplemental frame 30, 95 so that the operative relation of the bag delivery mechanism relatively to the folding and printing mechanisms and the delivery chute on the supplemental frame will not be disturbed when the supplemental 100 frame is adjusted.

By mounting the bag receiver in the manner described, it may be shifted, by sliding its carriage along the rods 210 to bring either of the bag-receiving compartments 110 thereof into position to receive the bags delivered by the delivery chute. For example, in Figures 24 and 24^a the left-hand compartment 200 is shown in position beneath the discharge end of the delivery chute, so that this compartment will receive and stack the bags as they are delivered, but by shifting the bag receiver and its carriage toward the left, the compartment 200 will 115 be moved out of bag receiving position and the right-hand compartment 200^a will be brought into such position. Means is provided for automatically shifting the bag receiver to interrupt the discharge of bags 120 into one of the compartments when such compartment has received a predetermined number of bags and to bring the other compartment into position to receive and stack the bags, and such means is so constructed 125 that it will effect the shift of the bag receiver 130

with such rapidity that the delivery of the bags from the machine will not be interrupted or interfered with. As shown, such means comprises a cross-head 213 and compression springs interposed between the opposite sides of the cross-head and the carriage. The compression springs 214 which may be conveniently mounted on the rods 210 in order to support them, are interposed between the left-hand side of the cross-head 213 and the left-hand slide bearings 209 of the carriage while other similar compression springs 215 are interposed between the right-hand side of the cross-head and the right-hand slide bearings 209. When the cross-head, which is guided on the rods 210, is shifted toward the left or right, it will compress the springs at the respective side thereof, and thereby tend to shift the carriage and the bag receiver toward the left or right. In Figure 24 the cross-head is shown shifted toward the left, the right-hand springs 215 being then uncompressed, while the springs 214 are compressed, and the tendency is for the bag receiver to shift toward the left under those conditions. The cross-head is moved alternately in left-hand and right-hand directions during the operation of the machine, and preferably this motion of the cross-head is a regular or gradual one. As shown, the cross-head is reciprocated by a connecting rod 216 which is pivotally connected at 217 to the cross-head and is operatively connected to a crank pin 218 which is carried by a crank disk 219, the latter being formed on or attached to a gear 220, this gear being mounted on a stud 221 which is supported on a cross-member 212^a of the frame 212. The gear 220 meshes with a gear 222, the latter being fixed on a shaft 223 which is journaled in bearings 224 and 225 attached to the lower portion 31 of the supplemental frame 30. This shaft 223 is constantly connected to and driven from the shaft 86, which, in turn, is driven from the lower folder roller shaft 48 through the worm wheels 87 and 88, by a bevel gear 226 on the shaft 223 which meshes with a bevel gear 227 which is fixed to the lower end of the shaft 86. The ratio of the gearing between the lower folder roll shaft and the crank driving gear 220 is such that the gear 220 will make a half revolution which will complete the throw of the cross-head 213 in one direction during the passage of any desired or predetermined number of bags through the machine. For example, if it is desired to stack fifty bags in each pile, the ratio of the gearing between the cross-head driving gear 220 and the lower folder roll shaft would be such that the gear 220 would complete a half revolution during fifty revolutions of the lower folder roll shaft, the latter shaft making one revolution for each bag which passes it. In order to enable timing of the strokes of the bag-receiver so that it will reverse its position during the interval between the successive deliveries of two bags, the crank 219 which carries the pin 218 70 may be secured adjustably to the gear 220 by bolts 228 which extend through circumferential slots 229 formed in the crank member, thus enabling the latter to be rotated to some extent relatively to the gear 210, and in order to provide an ample interval between the successive deliveries of the bags to the receiver for the reversal of the latter, during such interval, the belts 171 of the bag delivery chute are driven at such speed 75 that the speed of the bags will be doubled as they enter the chute from the printing mechanism. In order to properly set or adjust the range of movement of the cross-head, the pin 218 may be adjustably secured in a radial slot 218^a in the crank member. 80

While the cross-head 213 will advance more or less regularly during the passage of the bags through the machine, the bag receiver will occupy a stationary position with one or the other of its bag receiving compartments in position to receive the bags discharged from the delivery chute until the predetermined number of bags has been received by such compartment, whereupon the bag receiver will shift its position quickly to remove the filled compartment and to bring the other compartment into position to receive the bags. Automatic means is 90 provided by the present invention for effecting such operation of the bag receiver. Such mechanism comprises a pair of reversely arranged triggers 230 and 230^a, which are arranged to engage respectively 95 abutments 231 and 231^a on the carriage or bag receiver. As shown in Figures 24 and 25, the trigger 230 will engage the abutment 231 when the bag receiver occupies its right-hand position, the compartment 200 being 100 then in position to receive the bags from the delivery chute and the receiver being held in this position by the trigger 230. When the bag receiver is shifted to the left or into its left-hand position where the compartment 200^a is beneath the delivery chute to receive the bags therefrom, the trigger 230^a will engage the other abutment 231^a and the bag receiver will thus be held in its left-hand position. The triggers are pivotally mounted at 232 and 232^a on collars or brackets 233 and 233^a which may be clamped or otherwise suitably secured at appropriate points along the length of a rod 234, the latter extending in parallelism with the carriage supporting rods 210 and being secured and supported at its ends in the frame members 211. Springs 235 and 235^a act to yieldingly force the triggers into engaging relation with the abutments 231 and 231^a, re- 110 115 120 125 130

spectively, these springs acting on the tails 236 and 236^a of the respective triggers. The rod 234 supports a pair of trigger tripping collars 237 and 237^a, and between these 5 collars is mounted a tube or sleeve 238 which is mounted loosely on and is movable freely longitudinally of the rod 234, this tube or sleeve having a limited amount of lost motion or play between the collars 237 and 10 237^a. The tube 238 has abutment collars 239 and 239^a which are clamped or otherwise secured at proper points of adjustment along the tube and near the ends thereof. The cross-head 213 has a hub 240 which 15 moves loosely and longitudinally over the tube or sleeve 238 between the abutment collars 239 and 239^a.

The operation is as follows: Referring to Figures 24, 24^a and 25, it will be noted that 20 the left-hand bag compartment 200 is below the bag-delivery chute, the carriage occupying its right-hand position while the crank pin 218 has substantially reached its left-hand position, the cross-heads 213 being in 25 consequence shifted into its left-hand position and the springs 214 being compressed between the cross-head and the left-hand slide bearings 209 on the carriage, so that these springs are acting with a tendency to 30 shift the carriage to the left. The carriage, however, is retained in its right-hand position by the trigger 230 which engages its abutment 231. The parts occupy this position when a pile of bags comprising nearly 35 the full number of bags to be received by the compartment have been delivered, but as the delivery of the bags continues, the crank pin 218 will continue its movement toward the left until it reaches the dead center position, 40 and during this final portion of the movement of the crank pin toward the left the hub 240 of the cross-head 213 picks up the collar 239 on the sleeve 238 and shifts the tube 238 toward the left, forcing the collar 237 against the tail 236 of the trigger and 45 thereby retracting the latter from the abutment 231. The carriage is thereby released and it will make a rapid stroke toward the left under the influence of the compressed springs 214, and when this left-hand stroke 50 of the carriage has been completed, the other trigger 230^a will latch and engage the abutment 231^a, thereby holding the carriage in its left-hand position. This shift of the carriage 55 brings the other bag compartment 200^a into position beneath the delivery chute, so that as the bags continue their discharge from the machine, they are stacked in this compartment. The other filled compartment 60 200, which is shifted out of position beneath the delivery chute, will be in a position where the bags may be conveniently removed therefrom, and this compartment will be ready to receive another stack of bags

after the carriage has shifted back to its 65 former position. As the bags are delivered into the compartment 200^a, the cross-head 213 will be gradually shifted from the collar 239 to the collar 239^a, due to the right-hand stroke of the crank pin 218 during 70 the next half revolution of the driving gear 220, and when the cross-head reaches the collar 239^a, which occurs when the number of bags delivered to the compartment 200^a approaches the predetermined number 75 to be received by it, the collar 239^a is picked up by the cross-head and shifted toward the right in Figure 25, thereby shifting the tube 238 to the right in this figure, and when the cross-head reaches the limit of its right-hand movement the collar 237^a will have 80 engaged the tail 236^a of the trigger 230^a and rocked the same to release it from the abutment 231^a, thereby tripping the carriage and permitting it to shift rapidly toward the right under the influence of the springs 215 which will then be compressed while the springs 214 are uncompressed, the bag-filled compartment 200^a being thereby removed 85 from bag-receiving position and the compartment 200 brought into position to receive and stack bags delivered by the chute. The reversals in the position of the bag-receiver to cause the compartments therein to alternately receive the bags takes place automatically during the operation of the machine, and, moreover, the mechanism described may be adjusted so that each pile of bags will contain a predetermined number 90 95 100.

The ink-applying means for each type roll may consist, as shown in Fig. 31, of an ink fountain 251 containing an ink feeding roll 252, and a battery of freely revoluble rollers comprising a transfer roller 253 which receives ink from the feeding roller 252 and transfers it to a roller 254, a pair of rollers 255 which apply the ink to an inking roll 256 which transfers the ink to the type on the respective type roll through the intermediate rollers 257, and an ink distributing roller 258 which cooperates with the rollers 255. The ink feeding roller 252 is rotated periodically in feeding the ink from the fountain by a ratchet wheel 259 connected thereto and engaged by a pawl 260, the latter being carried by a member 261 which is mounted to rock about the axis of the roller 252 as a center and is actuated by a link 262 connected to an arm of a crank arm 263 fixed on a shaft 264, and another arm 265 fixed to said shaft is connected by a rod 266 to a crank pin 267 carried by the shaft of the roll 256 whereby during the operation of the printing mechanism, the ink feeding roll will be rotated intermittently. The roller 253 operates to receive ink from the periphery of the roller 252 and to transfer it to 110 115 120 125

the roller 254, for which purpose it is mounted at each end on an arm 268 fixed to the shaft 264, the roller 253 in consequence being swung to and fro between the rollers 252 and 254 coincident with the operations of the ratchet mechanism which advance the ink feeding roller.

Some or all of the rollers of the battery are provided with bearing mountings which enable these rollers or any of them to be easily removed whenever desired for cleaning or other purposes and to be replaced with facility. As shown, each end of the roller shaft 269 is reduced to form a journal 270 and an adjacent thrust shoulder 271, and each journal is provided with a sleeve-like bearing member 272 which is removable endwise relatively to the journal and is adapted to abut against the thrust shoulder 271. A bracket 273 is provided for each bearing member, each bracket being secured to the frame of the machine or other part thereof adapted to serve as a support, in some instances, by the bolts 274, and each is provided with a socket 275 in which the bearing member 272 is rotatable and also capable of insertion and removal by endwise movement thereof. A side of each socket is provided with a slot or opening 276 which is of a width somewhat greater than the diameter of the journal of the roller shaft so that the roller may be removed from the operative position by first removing the bearing members 272 endwise from the sockets and then passing its journals through the slots 276 of its brackets, and the roller may be similarly mounted while the bearing members are removed. However, the bearing members when inserted in their sockets close the sockets 276 owing to their greater diameter, and they provide bearings which support and prevent end play of the roller. Each bearing member is preferably locked in its socket to sustain end thrust from the roller and prevent its endwise displacement from the socket by providing the bearing member with a lug 277 which is capable of entering and moving endwise in the slot 276 to permit insertion or removal of the bearing member from the socket but which, when the bearing member has been inserted in the socket and rotated therein, enters a circumferential groove 278 within the socket and thereby locks the bearing member against endwise movement or displacement.

The operation of the machine in general is as follows: The paper tube from which the bag sections are to be cut is fed along the former 1 continuously by the operation of the draw rolls 4 and the bag sections are cut successively from this tube by the breaker arm 7 as it swings repeatedly past the end of the former, the tube forming and bag severing operations, however, being well un-

derstood to those skilled in this art as the 65 part of the machine for performing these operations is similar to that used in machines the construction and operation of which are well known.

Each bag section is received by the forwarding rolls 89 and 90 which operate to advance the bag section until its foremost end, which is to constitute the bottom of the finished bag, has been inserted to the proper extent between the nipping means on the upper folder roll 45 and the creaser blade 55 on the lower folder roll, these rolls being so timed with respect to the breaker bar and the forwarding rolls that the nipping means and creaser blade are about to come into 70 cooperative relation at this moment. The extent to which the leading end of the bag section is inserted past the creaser bar determines the depth of the fold which will be made at the bottom of the bag, and bottom 75 folds of different desired depths may be produced by appropriately adjusting the cam 100 which controls the timing and the duration of the period during which the forwarding rolls are in advancing engagement 80 with the bag section.

The portion of the bag section, at a suitable distance in rear of its leading edge, is engaged by the narrow edge of the creaser blade, and as the rotation of the upper and 95 lower folder rolls continues, the engaged portion of the bag section is pushed or forced by the creaser blade into the opening or crevice between the nipper blade 66 which is then in open position and the nipping 100 edge 64, thereby creasing the bag section sharply along the line where it is engaged by the creaser blade and introducing the thus doubled portion of the bag section between the nipper blade and the nipping 105 edge so that it will be nipped when the nipper blade swings into closed or nipping position.

The closing of the nipper blade on the creased edge of the bag section takes place 110 as the nipping means on the upper folder roll and the creaser blade on the lower folder roll are relatively moving apart due to the continued rotation of these rolls, and as the forward edge of the bag section beyond the nipped portion thereof is at this 115 time unrestrained, it will project approximately radially from the circumference of the upper folder roll. This projecting end of the bag section comes against the idler roll 108 during the further rotation of the upper folder roll and it is thereby folded smoothly down against that portion of the bag section in rear of the creased and nipped portion and which received paste from the paste bar, the idler roll applying sufficient pressure on the folder to insure firm adhesion thereof.

When the folded and pasted end of the bag section, still nipped and held by the upper folder roll, substantially reaches the bottom of the impression roll 107, the nipper 5 blade 66 is released by the riding of the roller 69 onto the cam 70, the grippers on the impression roll adjacent to the end of the bag section being at this time held open by the cam 145. As the nipper blade 66 is 10 retracted to release the nipped edge of the bag section, said nipped edge, acting under the inherent tendency of the paper comprising the bag section to straighten or flatten, snaps forward into the space between the 15 grippers and the opposed surface of the impression roll. As the rotation of the impression roll continues, the forward edge of the bag section, now released from the nipping means on the upper folder roll, rides 20 upon the doffers 153 which lie close to the surface of the impression roll and the roller 144 rides off the high part of the cam 145 thus allowing the grippers to snap into gripping engagement with the forward folded 25 edge of the bag under the action of their spring 151.

While the bag is thus held by the grippers, it is drawn past the printing roll 123, thus 30 receiving an impression from the type thereon, and then past the second printing roll 124 to receive another impression when impressions in inks of different colors are to be made. While the bottom fold of the bag is passing each printing roll, it is pinched 35 by the pinch bars thereon which have suitable recesses or clearances for the ends of the closed grippers as they pass the printing rollers.

After passing the last printing roll used, 40 the roller 144 rides up the high part of the cam 145, thereby swinging the grippers into open position and thus releasing the forward gripped edge of the bag. Upon release of this edge of the bag, such edge will 45 tend to swing outwardly away from the surface of the impression roll due to the inherent resilience of the paper, and this edge of the bag will be guided by the doffers 165 into the upper end of the delivery chute, the 50 complete transfer of each bag into the chute being insured by the rolls 166 which ride over the outer edges of the bag and thus press the bag against the surface of the impression roll which is moving in a direction 55 to push the bag into the chute.

The bags descend through and are delivered from the lower end of the chute into one or the other of the compartments of the bag receiver, a pile of bags of predetermined 60 number being formed in one compartment whereupon the bag receiver shifts automatically, as hereinbefore explained, to bring the other compartment into position to receive the bags and to stack them in a pile 65 containing a predetermined number.

The present invention provides a bag making and printing machine which is capable of operating rapidly and with certainty in the performance of its operations, of making the bags uniformly and with the desired 70 length or depth of bottom fold, and of insuring uniform and accurate registration of the printed impression or impressions thereon.

By nipping the bag section as it enters 75 the folding mechanism and thus holding it during its passage through such mechanism, displacement of the bag is avoided, and by providing forwarding rolls for advancing the bag sections to the folding mechanism, 80 uniformity of depth of the bottom flap on the completed bags is insured. By controlling the action of the forwarding rolls by a cam which is adjustable, the bottom fold may be adjusted to any depth desired. 85

The grippers which receive the leading edge of the bag as it is transferred to the impression roll avoid changing of the relative position of the bag as it is applied to the impression roll and they firmly and accurately hold the bag against displacement 90 relatively to the impression roll while the bag is being acted on by the printing roll or rolls, thereby insuring clear perfect impressions on the bags; and when the bags are 95 printed upon successively by a plurality of printing rolls, and especially when printed upon in different colors, accurate registration of the printed impressions is obtained as the bag is prevented from shifting its position during the printing operation or operations. Furthermore, by connecting or driving the folder rolls, and the impression and printing rolls through a train of gears all 100 of which are located at the same side of the machine, torsion of the roll shafts, which, if permitted to occur would impair the registration between these rolls and the bags is prevented. 105

The adjustment provided between the bag 110 section cut-off mechanism and the folding, printing and delivery mechanisms which are mounted on and form a unit with the supplemental frame enables the machine to be readily adjusted for the making and printing 115 of bags of different lengths, the folding, printing and delivery mechanisms accommodating themselves to the different adjustments of the supplemental frame.

By stacking the finished bags in piles each 120 containing a predetermined number of bags, as the bags are delivered from the machine, much time and labor are saved, as the piles of bags as they are removed from the delivery mechanism are ready to be bundled for packing and shipment. 125

I claim as my invention:—

1. In a bag making machine embodying means for advancing a paper tube and means for severing the same to form bag sections, 130

cooperative upper and lower folder rolls mounted to receive the bag sections between them, a creaser member carried by the lower roll, and a nipper carried by the upper roll 5 and operative to receive and nip a portion of the bag section creased by said creaser member and thereby attach the bag to the upper folder roll.

2. In a bag making machine embodying 10 a former, means for advancing a paper tube along the former, a severing blade arranged beneath the former, and means for severing such tube into bag sections, cooperative upper and lower folder rolls to which said 15 bag sections are fed, a creaser blade projecting from the periphery of the lower roll, and nipping means carried by the upper roll comprising a movable nipper blade operative to nip an edge of the bag section creased 20 by the creaser blade and thereby attach the bag section to the upper roll.

3. In a bag-making machine embodying a former and means for advancing a paper tube along it, a severing knife arranged beneath the former, a breaker arm movable 25 downwardly past the former and cooperative with the severing knife to sever said paper tube into bag sections, bottom folder rolls arranged to receive the bag sections 30 and operative to form the bottom folds of the bags and to carry the bags upwardly above the former, and bag printing means located above the folder rolls and arranged to receive the bags therefrom.

4. In a bag-making machine embodying a former and means for advancing a paper tube along it, a severing knife arranged beneath the former, a breaker arm movably 40 downwardly past the former and cooperative with the severing knife to sever said paper tube into bag sections, upper and lower folder rolls arranged to receive the bag sections between them, the upper folder roll having means for attaching the bag 45 sections to its periphery, and bag-printing means located above the folder rolls and arranged to receive the bag sections therefrom.

5. In a bag-making machine embodying 50 means for feeding bag sections, bottom folder rolls arranged to receive the bag sections and operative to carry them upwardly above said feeding and severing means, and an impression roll located above the folder rolls, and printing mechanism located above the 55 impression roll and cooperative therewith.

6. In a bag making machine embodying 60 means for feeding a paper tube and means for severing such tube into bag sections, upper and lower folder rolls arranged to receive the bag sections, the upper folder roll having means for nipping the bag sections and carrying them upwardly, an impression roll arranged above the upper fold-

er roll and having gripping means for carrying the bag sections upwardly, printing mechanism arranged above and cooperative with said impression roll, and means for delivering the printed bags downwardly 65 from the printing mechanism. 70

7. In a bag making machine, cooperative folder rolls arranged to receive bag sections between them, a creaser blade on one of said rolls, a nipper blade operative in a recess of the other roll to nip a portion of a bag 75 section creased by the creaser blade, the leading edge of the bag section in advance of the nipped portion thereof being free to project from the surface of the roll carrying the nipper blade, a roller cooperative with the surface of the nipper blade carrying roll to fold said projecting edge of the bag section against the portion of the bag section in rear of the nipped portion thereof, 80 brackets supporting said roller and means 85 cooperative with said bracket for preventing inward movement of said roller while the recess in the nipper blade carrying roll is opposite thereto.

8. In a bag making machine of the class 90 embodying means for advancing a paper tube and means for severing such tube into bag sections, cooperative folder rolls to receive the bag sections, forwarding rolls mounted to engage and advance the bag 95 sections to the folder rolls, and means for causing the forwarding rolls to act periodically on the bag sections.

9. In a bag making machine of the class 100 embodying means for advancing a paper tube and means for severing the same to form bag sections, cooperative folder rolls arranged to receive the bag sections forwarding rolls arranged to secure the bag sections and operative to advance the same 105 to the folder rolls, and means for rendering the forwarding rolls inactive with respect to each bag section after the same has been advanced to a predetermined extent between the folder rolls. 110

10. In a bag making machine of the class 115 embodying means for advancing a paper tube and means for severing the same into bag sections, cooperative folder rolls arranged to receive the bag sections between them, forwarding rolls having means for rotating them continuously and operative to engage and advance the bag sections to the folder rolls, and means for relatively separating the forwarding rolls to interrupt 120 the advance of the bag sections thereby when the latter have been advanced to a predetermined extent between the folder rolls.

11. In a bag making machine of the class 125 embodying means for advancing a paper tube and means for severing such tube into bag sections, folder rolls having cooperative folding means thereon, forwarding rolls ar-

- ranged to receive the bag sections and operative to advance them to the folding means on the folder rolls, and means timed relatively to the folder rolls for interrupting the advancing action of the forwarding rolls when each bag section has been advanced to a predetermined extent in relation to the folding means on the folder rolls. 5 to act on the bag sections, the folding means 65 on one of the rolls comprising a nipper blade movable relatively to said roll to engage and release a bag section, and a cam the operative length of which is variable to control the engaging and releasing movements of the nipper blade. 70
12. In a bag making machine of the class embodying means for advancing a paper tube and means for severing the same into bag sections, cooperative folder rolls having bag folding means thereon, forwarding rolls arranged to receive the bag sections and operative to introduce them successively to the folding means thereon, and variable means for determining the extent of advance of the bag sections according to the length of fold to be made on the bag 10 section. 13. In a bag making machine of the class embodying means for advancing a paper tube and means for severing the same into bag sections, cooperative folder rolls arranged to receive and advance the bag sections between them and carrying folding means to operate on the bag sections, forwarding rolls arranged to receive the bag sections between them and relatively movable into engagement therewith to advance them to the folder rolls, and means including a cam operative in timed relation with the folder rolls for interrupting the bag section advancing action of the forwarding rolls when each bag section has been advanced to a predetermined extent with respect to the folding means on the folder rolls, said cam being adjustable to vary the extent to which the bag sections are advanced with respect to the folding means. 25 30 35 40 14. In a bag making machine, cooperative folder rolls, cooperative forwarding rolls mounted in advance thereof for feeding bag sections thereto, means for causing the forwarding rolls to grip and advance the bag sections, means including a rock shaft operative to relatively separate the forwarding rolls to interrupt the advance of the bag sections thereby, and a cam rotatable with one of the folder rolls and operative upon the rock shaft to control the bag section feeding action of the forwarding rolls. 45 50 55 60 15. In a bag making machine, a folder roll carrying a creaser blade, a shaft supporting said roll, split clamps on said shaft at opposite ends of said roll, and a paste bar adjacent to the creaser blade and supported at its ends by said clamps, said clamps being adjustable angularly about said shaft to adjust the paste bar in a direction circumferentially of said roll. 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930
17. In a bag making machine, cooperative folder rolls carrying folding means, the folding means on one roll comprising a nipper blade movable into and out of nipping relation with a portion of a bag section, and a cam having portions which are relatively adjustable to time the engagement of the nipper blade with the bag section when the folding means of the folder rolls are in cooperative relation and to independently time the release of the bag section by the nipper blade. 18. In a bag making machine, cooperative folder rolls carrying folding means, the folding means on one of said rolls embodying a movable nipper blade, another roll cooperative with the folder roll carrying the nipper blade and carrying grippers, means for operating the nipper blade to release a bag section when the latter is in a position in proximity to the grippers, and means for holding the grippers in open position when the nipper blade releases the bag section and for causing closing of the grippers to engage the released bag section. 19. In a bag making machine, cooperative rolls mounted to advance bag sections between them, one of said rolls carrying a nipper blade to engage and hold an end of a bag section thereon, and the other roll carrying grippers operative to grip said end of the bag section after its release by said nipper blade, and controlling means for the nipper blade and grippers, whereby the nipper blade will release the end of the bag section and the grippers will be in position to receive the latter when said end of the bag section is substantially at the nip of said rolls. 20. In a machine of the class described, cooperative rolls mounted to receive and advance bag sections between them, one of said rolls carrying nipping means to engage and hold the leading end of a bag section during its advance around such roll and operative to release the bag section substantially when its leading end reaches the nip between said rolls, grippers carried by the other roll and operative to engage the leading end of the bag section, and means for holding the grippers in open position and projecting outwardly beyond the surface of its respective roll to receive the leading end of the bag section and for closing the grippers to engage said end of the bag section after its release by the nipping means. 21. In a machine of the class described,

- 1 a roll adapted to receive bag sections successively, and means for gripping and holding each bag section on said roll comprising a shaft, grippers loosely mounted thereon, 5 collars fixed to the shaft, toothed clutch members between the grippers and the respective collars and which permit relative rotation between them, and means between the grippers and their respective collars for 10 individually and yieldingly forcing them into gripping engagement with a bag section on the roll.
22. In a machine of the class described, a roll carrying grippers for advancing a bag 15 thereon, rollers arranged to bear on the bag on the roll, and means for retracting the rollers to clear the grippers during the passage of the latter.
23. In a machine of the class described, 20 an impression roll, a printing roll cooperative therewith, and a pair of rollers having means for individually pressing them yieldingly against a bag on the impression roll after it has passed the printing roll to strip 25 the bag from the latter roll.
24. In a machine of the class described, an impression roll, a cooperative printing roll, a stripper roll having means for yieldingly pressing the stripper roll against a 30 bag on the impression roll, and means for retracting the stripper roll relatively to the impression roll as the leading end of the bag approaches the stripper roll.
25. In a machine of the class described, 35 an impression roll, a cooperative printing roll, a pair of stripper rolls to engage a bag on the impression roll after the bag has passed the printing roll, means for individually pressing the stripper rolls toward the impression roll and means for retracting the stripper rolls from the impression roll.
26. In a machine of the class described, 40 an impression roll, a cooperative roll for advancing a bag thereto, doffers for transferring the bag to the impression roll, and grippers on the impression roll arranged to receive and operative to grip the leading edge of the bag.
27. In a machine of the class described, 45 a printing roll, an impression roll for advancing a bag thereto for printing, and a smoothing plate having means for yieldingly pressing it against a bag on the impression roll as such bag is advanced to the printing roll.
28. In a machine of the class described, 50 a printing roll, an impression roll for carrying a bag between it and the printing roll, stripping rolls movable toward and from the impression roll for stripping a printed bag from the printing roll, and strippers movable into operative position in unison with the stripping rolls for removing the printed bag from the impression roll.
29. In a machine of the class described, co-operative bag impression and printing rolls operative to deliver a printed bag between them, a chute arranged to receive a bag delivered by said rolls, stripper rolls adjacent to the entrance of the chute operative to bear 70 on a printed bag delivered from the impression and printing rolls and strip the printed bag from the printing roll, and strippers also adjacent to the inlet of the chute and adapted to occupy a position between the 75 bag and the impression roll to remove the bag from said roll.
30. In a bag making machine, the combination of mechanism for forming a paper tube and for severing the same into bag sections, and folding mechanism having printing means arranged above it and operative 80 upon the bag sections to complete them, said mechanisms being relatively adjustable to vary the distance between them and thus 85 accommodate them to the making of bags of different lengths.
31. In a bag making machine, the combination with mechanism for forming a paper tube and for severing the same into 90 bag sections, of folding mechanism operative to receive the bag sections successively, bag delivery means cooperative with the folding mechanism, and means for bodily shifting the folding mechanism and bag delivery means relatively to the paper tube 95 forming and severing mechanism to accommodate said mechanisms to the making of bags of different lengths.
32. In a bag making and printing machine, the combination of cooperative folder rolls operative to make the bag bottom folds on bag sections introduced between them, an impression roll operative to receive the bags from the folder rolls, a printing roll 100 cooperative with the impression roll, all of said rolls being arranged to form a series and a train of connecting gearing for said series of rolls arranged at the same side 105 thereof.
33. In a machine of the class described, an impression roll for advancing a bag having a bottom fold, a cooperative printing roll, and means carried by the printing roll and arranged to press the bottom fold of the bag against the surface of the impression roll.
34. In a machine of the class described, 110 an impression roll for advancing a bag having a bottom fold, and a cooperative printing roll having a pinch bar projecting from its periphery and operative to press the bottom fold of the bag against the impression roll.
35. In a machine of the class described, 115 an impression roll for advancing a bag having a fold, a cooperating printing roll, a pinch bar movable radially of the printing 120
- 125

roll, and means for causing the pinch bar to move outwardly and to press against the fold of the bag as the latter is advanced past the printing roll.

5 36. In a machine of the class described, cooperative rolls for advancing a bag having a bottom fold, and means carried by

one of said rolls and movable outwardly from its periphery to pinch the bottom fold of the bag against the surface of the other roll.

In testimony whereof I have hereunto set my hand.

TRUE M. AVERY.
